DESIGN.

—o—

W. L. JACOBS.

CARPET.

No. 17,484.

Patented July 26, 1887.

UNITED STATES PATENT OFFICE.

WINTHROP L. JACOBS, OF EAST ORANGE, NEW JERSEY, ASSIGNOR TO THE
HARTFORD CARPET COMPANY, OF HARTFORD, CONNECTICUT.

DESIGN FOR A CARPET.

SPECIFICATION forming part of Design No. 17,484, dated July 26, 1887.

Application filed June 15, 1887. Serial No. 241,432. Term of patent 3½ years.

To all whom it may concern:

Be it known that I, WINTHROP L. JACOBS, of East Orange, New Jersey, have invented a new and original Design for Carpets, of which 5 the following is a specification, reference being had to the accompanying photograph, which forms a part of the same.

The invention relates to a design to be worked into or upon surfaces, such as carpets 10 or similar fabrics; and it consists in the novel configuration and grouping of figures herein specifically shown and claimed.

The accompanying photograph is a face view 15 of a carpet showing my new design.

15 The main feature of my design consists in the assembling of a number of composite figures or groups, each of which is made up of a number of varied geometric or conventional forms united by angular stem-work.

20 Group A is composed of a large fan shaped figure, a shield-shaped figure, a number of diamond-shaped figures, and smaller circular forms, all disposed irregularly and connected by a fanciful angular stem-work.

25 Group B (shown at the bottom and the top of the photograph) is a long narrow group, and consists of a middle vine or stem having small star-shaped flowers or leaves scattered along it, and a fan form, a diamond form, and oval forms with smaller figures clustered around the vine.

Group C (shown at the right-hand side and

the upper left-hand corner of the photograph) 35 consists of a large circular figure representing a mass of leaves, whose projecting points form the outline of the figure, with smaller circular figures and other geometric forms united by an angular stem or vine work.

Group D (shown at the middle of the right side of the photograph and at the lower left-hand corner) consists of a large central fan-shaped figure, a heraldic form, and smaller oval and circular forms connected by a vine or angular stem work.

Group E (shown at the upper right-hand 45 corner and lower left side of the photograph) consists of a large fan-shaped figure, several leaf figures, and smaller skeleton figures connected by a vine or stem work.

Group F consists of a large partly-crown-shaped figure with a smaller one of similar shape and a large variety of small circular and stem shaped figures united by a vine or stem work.

All of these groups are clearly shown in the 55 photograph in all their details.

What I claim as new, and desire to secure by Letters Patent, is—

The design for carpets, consisting of the design substantially as shown.

W. L. JACOBS.
